CLAIM

The ornamental design for a tote bag, as shown and described.

DESCRIPTION

FIG. 1 is a top perspective view of a tote bag;

FIG. 2 is a front side view of the tote bag;

FIG. 3 is a back side view of the tote bag;

FIG. 4 is a left side view of the tote bag;

FIG. 5 is a right side view of the tote bag;

FIG. 6 is a top view of the tote bag;

FIG. 7 is a bottom view of the tote bag; and,

FIG. 8 is a bottom perspective view of the tote bag shown compacted.

In the drawings, the broken lines are understood to represent stitching.
